2 Sheets-Sheet 2

Fig. 6

Fig. 7

The diagram illustrates a cable structure, likely a fiber optic cable, with the following labeled components:

- 13: A label near the top left.
- 50: A label near the top center.
- 15a: A label pointing to a specific section of the cable's outer jacket.
- 21: A label pointing to a central fiber or a specific section of the cable's internal structure.
- 22: A label pointing to another section of the internal structure.
- 37: A label pointing to a section of the outer jacket.
- 15: A label pointing to the outer jacket.
- 30: A label pointing to the outer jacket.
- 31: A label pointing to the outer jacket.
- 15: A label pointing to the outer jacket on the right side.

TURN SHOE

Charles Miller, Long Island City, N. Y.

Application April 16, 1934, Serial No. 720,723

11 Claims. (Cl. 12—142)

This invention relates to the shoe art and deals more specifically with a new and improved shoe structure including a novel shank construction.

It is an object of this invention to produce a lady's shoe having all the desirable qualities as to flexibility and appearance and having at the same time a continuous sweep of the upper over the shank, without the usual outsole piece at the shank between the tread surface of the sole and the breast of the heel.

A further object of this invention is to make a turn shoe in which the shank portion of the finished product is covered by the upper material.

And it is a further object of this invention to produce a turn shoe having exposed upper material at the shank instead of the usual shank portion of the outsole, without substantially altering the standard practice of making turn shoes.

These and other objects of the invention will be readily apparent to those skilled in the art from the following description taken in conjunction with the accompanying drawings, in which:

Fig. 1 is a perspective view of the bottom of a shoe embodying the present invention.

Fig. 2 is a perspective view showing a shoe assembled inside out on the last, after the first lasting.

Fig. 3 is a cross section taken on the line 3—3 of Fig. 1.

Fig. 4 is a schematic view of a sole used in this shoe.

Fig. 5 is a view similar to Fig. 1 showing a modification.

Fig. 6 is a section in the line 6—6 of Fig. 5.

Fig. 7 is a section similar to that of Fig. 6 showing the shoe inside out prior to the operation of turning.

Fig. 8 is a sectional view similar to Fig. 6 showing a modification.

Referring in detail to the drawings, the shoe is seen to comprise the upper 11, heel 12, and outsole 13. The upper is made up of the vamp 14, forward quarters 15 and rear quarters 16.

An outsole 13 of the type commonly used in making turn shoes, channelled at 20 to provide the lip 21, is split from the rear forwardly to the ball line to provide the main sole portion 22 and flap 23. The flap 23 is of a thickness usually provided in such outsoles for the purpose of covering the shank portion of the shoe and serving as the breast covering for the heel. After the splitting operation, the shank portion 24 of the flap 23 is cut away, leaving the piece 25 which is to serve as the heel breast, and leaving also the portion 26 which serves as the tread surface of the sole. A cellulose cement is applied to the heel portion of the surface between the portion 22 and the flap 23 prior to the cutting away of 24, and the cemented parts are rendered suffi-

ciently tacky to hold the piece 25 detachably in place on the sole until the shoe is ready for the attachment of the heel and the breast cover.

An outsole thus prepared is tempered and tacked on a last with the lip 21 exposed. An upper 14—16, doubler 30 and lining 31 cut to the desired shape are now assembled over the last 33, pulled over and tacked in place temporarily. A counter 32 is inserted between the lining and the doubler and is also tacked to the last, especially around the heel. The operations thus far described are well understood in the art of turn shoe manufacture.

In shaping the upper, doubler and lining prior to the lasting operation, an extension 15a is formed on the quarter 15 of the upper, but the lining and doubler are shaped in the normal way. As seen in Fig. 2 the extension 15a is tucked under the shank part of the outsole between the same and the last, and turned over onto the sewing lip 21. When the shoe is lasted, the extension 15a is pulled taut to take out any stretch which might be in the material forming this part. The extension 15a is tacked down by tacks 36 to hold the same in place until the sewing operation. In the present embodiment the extension 15a is formed on the outer side of the upper and extends over to the inner side. For example, for a right shoe the extension extends from the right to the left, as the wearer sees the shoe.

The sewing operation is now carried out. Referring to Figs. 2 and 3, stitches 37 are passed into the channel 20 through the lip 21, and through the counter, doubler, lining and upper, the stitches being run completely around the periphery of the shoe. It will be understood that at that portion where the flap 15a is tucked under the outsole (Fig. 2) only the lining, doubler, and counter are stitched to the lip 21 on the outer side of the shoe (Fig. 3), while on the inner side of the shoe the flap or extension 15a together with the lining, doubler, counter, and upper are stitched to the lip. For the sake of clarity in this description the side marked A (Fig. 3) is referred to as the inner side while the side marked B is referred to as the outer side.

After the sewing, the surplus material is trimmed away and the shoe is turned right side out, the parts thus assuming the relative positions as illustrated in Fig. 3.

The heel is attached and the flap 25 is applied to the breast thereof. Referring to Fig. 4 it will be noted that the portion 26 comes to a point 26a which is suitably shaped to give a neat appearance when the shoe is completed. Of course, the extension 15a extends under the point 26a. The usual finishing operations are performed to complete the shoe.

By virtue of the present invention the shank portion of the shoe is not broken up by the por-

tion of the outsole which usually comes at this point, but rather the quarter is one continuous piece extending from the top marginal edge of the upper completely around to the sewing lip on 5 the side A (Figs. 1 and 3). This gives the desirable results of permitting one continuous design to be applied to the part 15a as a continuation of the ornamentation 40 on the quarter (Fig. 1). The novel shankless construction is 10 also realized by virtue of the foregoing construction.

The foregoing structure deals with a shoe in which extension 15a terminates on the inner side A of the shoe. Under certain circumstances it is desirable that the extension run from the inner side A and terminate on the outer side B of the shoe. This result may be had in accordance with the principles of the present invention, as more fully hereinafter explained.

20 Referring in detail to Figs. 5, 6, and 7 a shoe having the same construction as that shown in Figs. 1-3 is disclosed, similar reference characters being applied to similar parts. In constructing this modification, the same procedure
25 is followed as in the making of the first modification, with the exception that the flap 15a is formed on that part of the upper which comes at the inner side (A) and is brought under the sole through to the outer side (B) where it is
30 sewed to the lip 21. (Figs. 6 and 7.)

Thus it will be seen that a shoe embodying the principles of the present invention may be constructed with the junction of the extension 15a with the lip 21 either on the inner or outer side 35 of the shoe, as desired.

Now, for certain styles of women's shoes it is desirable to further modify the invention by shaping the contour of the shank portion of the shoe to produce a triangular effect. This is accomplished for example by inserting a strip of leather 50, having a triangular cross section, between the extension 15a and the sole part 22, as illustrated in Fig. 8, and cementing the same in place. The strip 50 extends under the parts 26a and 25.

45 Obviously the cross section of 59 may be of any desired configuration, depending upon the effect desired. Also, instead of using the strip 50 the adjacent surface of 22 may be properly shaped to give the desired effect.

50 Having thus described my invention, I claim:

1. A shoe of the class described having a sole
an upper, a shank portion and a heel, said upper
being attached to said sole around the entire pe-
riphery thereof except on one side of the shank
portion, said upper extending across said shank
portion from one side to the other, said sole having
an exposed forward portion in the finished shoe
terminating adjacent the forward part of said
shank portion of the upper.

60 2. A shoe of the class described having a sole, a heel, a shank portion, and an upper, said upper being provided with an extension, said upper being sewed to said sole completely around the periphery thereof, except at the shank portion where
65 the extension is joined to said upper, the said extension being brought across said shank portion and sewed to said sole, said extension being exposed for substantially the full width thereof externally of the shoe, and said sole having an exposed forward portion terminating adjacent to the forward part of said extension.

3. A turn shoe comprising a sole provided with a channel and lip to receive stitches, an upper stitched to said lip, except at one side of the

shank portion of said sole, and having a section extending across said shank portion and stitched to the other side thereof and a heel attached to said shoe.

4. A turn shoe comprising in combination, a sole, an upper attached to said sole, a portion of said sole being cut away at the shank, and a covering of the said upper extending across said portion and attached to the marginal portion of said sole. 10

5. A turn shoe comprising in combination, a sole, an upper attached to said sole, a portion of said sole being cut away at the shank, an extension formed on said upper, said extension being drawn across said cut away portion and having its edge attached to the marginal portion of said sole.

6. A turn shoe having a sole provided with a lip to which the upper is to be sewed, an upper, said upper being sewed to said lip peripherally thereof except for a predetermined part, that portion of the upper which is adjacent to said last mentioned part being brought across said sole and sewed to the lip on the opposite side of the shoe. 25

7. A turn shoe comprising in combination, an outsole having a forward part, a shank part, and a heel part, an upper, said upper being sewed to said forward part and said heel part, and said upper extending across said shank part from one side of the shoe to the other side of the shoe, said upper being unattached to said shank portion on one side and attached thereto on the other side. 30.

8. The method of making turn shoes which comprises, mounting on a last an outsole having a sewing lip, lasting an upper, having an extension and attached lining over said last and temporarily attaching same to said sole, inserting said extension under said sole, inserting a counter between the upper and the lining, sewing the upper and lining and counter to said lip, pulling the edge of said extension over onto said lip, removing the last, turning the shoe, and finishing the same. 35 40

9. The method of making turn shoes which comprises preparing a sole with a lip to receive stitches, splitting said sole to provide a heel breast and a shank portion, cutting away the shank portion of said split part, mounting said sole on a last, lasting an upper having an extension over said last and temporarily tacking the same to said sole, pulling said extension through under said sole and tacking it to said lip, sewing said upper and the extension to said lip, turning the shoe, attaching a heel and a heel breast and finishing the shoe. 55

10. The method of making shoes which comprises splitting a sole from the heel to substantially the ball line, removing heel and shank sections from one of the split portions forming a sole of reduced thickness at the heel and shank, attaching an upper to said sole with the full width of the reduced shank portion thereof covered by the upper, and finishing the shoe. 60

11. The method of making shoes which comprises lasting an upper wrong side out and attaching the same to a sole by extending a portion of the upper from one side of the shank there-across to the other side of the shank and securing it to the sole at the last mentioned side of the shank, removing the last, turning the shoe, and finishing the shoe. 65 70
